TAP CLAMP

Ralph R. Pittman and Carroll H. Walsh,
Pine Bluff, Ark.

Application June 10, 1938, Serial No. 212,943

3 Claims. (Cl. 173—273)

This invention relates generally to devices for electrically connecting conductors, and particularly to so-called "hot line" clamps employed in connecting a tap wire to an energized high voltage conductor.

Among the objects of the present invention may be noted the provision of means for clamping a tap wire in direct engagement with a conductor, thereby avoiding the use of the clamp body as 10 a conductor, and also the use of a connecting device for attaching the tap wire to the body of the clamp.

Another object is the provision of means for combining the tap wire with the clamp so that the tap wire may be formed into an eye positioned at the top of the clamp for use in applying the clamp to and removing the clamp from the connected conductor.

These and other objects will appear as the description proceeds, and the scope of the invention will be set forth in the appended claims.

In the drawing, Fig. 1 is a side elevational view of the invention, and Fig. 2 is a fragmentary sectional view along the line II—II of Fig. 1.

Referring in detail to the drawing, a hollow body portion 10 having an opening in one side thereof is provided with an inverted V-shaped upper portion 15. A rotatively movable member 11 extends through and threadedly engages a horizontally extending portion of the body portion 10, and is provided with an eye 12 for convenient manipulation. The upper end of the member 11 is provided with a shoe 13, which is vertically movable with the member 11 toward and away from the hollow of the V-shaped portion 15, and along the body portion 10.

A pair of openings 16 and 17, having their axes positioned in intersecting planes which are substantially normal with respect to each other, extend through the body portion 10 along the inside surface of the respective legs of the V-shaped portion 15. The openings 16 and 17 are so positioned that a tap wire threaded therethrough has portions thereof extending along the inside surface of the respective legs of the V-shaped portion 15, and positioned within the hollow of the V.

In applying the clamp, a tap wire 18 is first passed upwardly through the opening 16, and the end thereof then passed downwardly through the opening 17, and finally the end portion 20 anchored by being bent back upwardly over the outwardly extending portion of the body portion 10. Such an operation results in the formation of a loop 19 in the tap wire 18, the loop 19 being

positioned above the body portion 10 in a convenient location for use in hooking the assembly over a conductor 14, by means of a switch stick or other suitable tool. After the assembly is in the hooked position with the tap wire 18 engaging the conductor 14 at two spaced points therealong, the eye 12 is rotated to urge the shoe 13 against the conductor 14.

It may be observed that the organization just described makes possible the omission of two elements commonly found on clamps for this purpose; first, an eye integral with the body portion at the upper end thereof, and second, a device for connecting the tap wire to the body portion of the clamp.

It will also be apparent that the body portion of the clamp is not interposed in series circuit relation with the tap wire, and that therefore it may be constructed of any inexpensive material having the desired mechanical strength without regard to the matter of electrical conductivity.

Since the shoe 13 is arranged to hold the conductor 14 in tight engagement with two points along the tap wire 18, a lower resistance connection may be provided than is possible with the use of fewer contact points between the conductor and the tap wire, or with arrangements having a greater number of contact points in series circuit relation with the tap wire.

From the above description, it will be seen that we provide a simple, effective and easily and inexpensively constructed tap clamp.

It will be understood that the drawing and description herein are intended as illustrative rather than limiting, also that various modifications of our invention may be made without departing from the principles of the invention, and our invention is to be limited only as is necessitated by the claims and the prior art.

We claim, as our invention:

1. In a clamp for connecting a tap wire to an electrical conductor, a body portion having an inverted V-shaped hollow at the upper end thereof, a clamping shoe movable along said body portion, adjustable means for moving said shoe toward said hollow to clamp the conductor between said body portion and said shoe, and holding means formed in said body portion for maintaining said tap wire in physical engagement with said conductor, said holding means comprising a lower opening of circular cross-section extending upwardly through said body portion in a direction substantially parallel to one leg of said inverted V-shaped hollow to the lower extremity of one leg thereof, a groove of substantially semi-

circular cross-section extending longitudinally along the inner surface of said one leg and merging with said lower opening, and an upper opening of substantially circular cross-section extending from the juncture of the legs of said V-shaped hollow in axial alignment with said lower opening, said tap wire extending upwardly into said body portion through said lower opening and emerging from said body portion through said upper opening, that portion of said tap wire between the lower and upper openings extending along said semi-circular groove.

2. In a clamp for connecting a tap wire to a conductor, a body portion having an inverted V-shaped hollow at the upper end thereof, a clamping shoe movable along said body portion, adjustable means for moving said shoe toward said hollow to clamp the conductor between said body portion and said shoe, and holding means within said body portion for maintaining said tap wire in direct physical engagement with said conductor, said holding means comprising a pair of laterally spaced openings extending upwardly through said body portion along the legs of said inverted V-shaped hollow and in communication therewith, said openings lying in parallel planes

which are normal to the axis of said conductor and in intersecting planes which are parallel to the axis of said conductor.

3. In a clamp for connecting a tap wire to a conductor, a body portion having an inverted V-shaped hollow at the upper end thereof, a clamping shoe movable along said body portion, adjustable means for moving said shoe toward said hollow to clamp the conductor between said body portion and said shoe, and holding means within said body portion for maintaining said tap wire in direct physical engagement with said conductor, said holding means comprising a pair of laterally spaced openings extending upwardly through said body portion along the legs of said inverted V-shaped hollow and in communication therewith, said openings lying in parallel planes which are normal to the axis of said conductor and in intersecting planes which are parallel to the axis of said conductor, said tap wire extending first upwardly through one of said openings and then downwardly through the other of said openings to thereby form a loop above said body portion for cooperating with a manipulating tool.
